[57] CLAIM

The ornamental design for a belt loop watch case, as shown.

DESCRIPTION

FIG. 1 is a front elevational view of a belt loop watch case showing my new design;

FIG. 2 is a right side elevational view;

FIG. 3 is a left side elevational view;

FIG. 4 is a rear elevational view;

FIG. 5 is a bottom plan view;

FIG. 6 is a top plan view;

FIG. 7 is a front elevational view of a second embodiment of my new design of FIG. 1-6;

FIG. 8 is a right side elevational view;

FIG. 9 is a rear elevational view;

FIG. 10 is a bottom plan view; and

FIG. 11 is a top plan view thereof.
